UNITED STATES PATENT OFFICE.

CHRISTIAN BICKEL, OF SPRINGFIELD, OHIO.

DESIGN FOR A CURTAIN-HOOK.

SPECIFICATION forming part of Design No. 24,540, dated August 13, 1895.

Application filed March 25, 1895. Serial No. 543,159. Term of patent 7 years.

To all whom it may concern:

Be it known that I, CHRISTIAN BICKEL, a citizen of the United States, residing at Springfield, in the county of Clark and State of Ohio, 5 have invented and produced a certain new and original Design for Curtain-Hooks, of which the following is a specification, reference being had therein to the accompanying drawing.

In the accompanying drawing the figure is a side elevation of my new design for a curtain hook.

The leading feature of my design consists of a curtain-hook formed of an open substantially rectangular body and a projecting

prong. The hook has a body composed of a long side *a* and short side *b*, a top bar *c* and a bottom bar *d*, and the hook proper consists of a projecting bar *e* with a point *f*.

Having thus fully described my invention, 20 what I claim as new, and desire to secure by Letters Patent, is—

The design for a curtain hook herein shown and described.

In testimony whereof I affix my signature 25 in presence of two witnesses.

CHRISTIAN BICKEL.
